(57) **CLAIM**

We claim the ornamental design for a slide out waste container shelf, as shown and described.

DESCRIPTION

FIG. 1 is a top perspective view of a slide out waste container shelf.

FIG. 2 is a front elevation view of the slide out waste container shelf of FIG. 1.

FIG. 3 is a rear elevation view of the slide out waste container shelf of FIG. 1.

FIG. 4 is a left side elevation view of the slide out waste container shelf of FIG. 1.

FIG. 5 is a right side elevation view of the slide out waste container shelf of FIG. 1.

FIG. 6 is a top plan view of the slide out waste container shelf of FIG. 1; and,

FIG. 7 is a bottom plan view of the slide out waste container shelf of FIG. 1.

The broken lines represent portions of the slide out waste container shelf and form no part of the claimed design.
